UNITED STATES PATENT OFFICE.

RAY SMITH, OF PLACENTIA, CALIFORNIA.

DESIGN FOR A SAFETY-PIN.

47,674.

Specification for Design.

Patented Aug. 3, 1915.

Application filed May 22, 1915. Serial No. 29,914. Term of patent 3½ years.

To all whom it may concern:

Be it known that I, RAY SMITH, a citizen of the United States, residing at Placentia, in the county of Orange and State of California, have invented a new, original, and ornamental Design for Safety-Pins, of which the following is a specification, reference being had to the accompanying drawing, forming a part thereof.

The figure is a plan view of a safety pin showing my new design.

I claim:

The ornamental design for a safety pin, as shown.

In witness that I claim the foregoing I have hereunto subscribed my name this 14th day of May, 1915.

RAY SMITH.
